PADDLE FOR GAMES

Richard E. Wagner, 131 Mayer Drive, Savannah, Ga.

Filed Apr. 12, 1961, Ser. No. 64,765

Term of patent 14 years

(Cl. D34—5)

FIG. 1 is a front elevational view of the paddle for games;

FIG. 2 is a side elevational view of the paddle for games embodying my new design; and

FIG. 3 is a bottom view of the paddle for games.

The side of the paddle for games opposite that shown in FIG. 1 is substantially the same as the side shown in FIG. 1.

I claim:

The ornamental design for a paddle for games, as shown and described.
